UNITED STATES PATENT OFFICE.

THOMAS SUTHERLAND, OF HUTCHINSON, MINNESOTA, ASSIGNOR OF THREE-FOURTHS TO GUS R. ZICKRICK, OF HUTCHINSON, MINNESOTA.

WIRE FABRIC.

SPECIFICATION forming part of Letters Patent No. 757,244, dated April 12, 1904.

Application filed February 10, 1902. Serial No. 93,324. (No model.)

To all whom it may concern:

Be it known that I, THOMAS SUTHERLAND, a citizen of Canada, residing at Hutchinson, in the county of McLeod and State of Minnesota, have invented certain new and useful Improvements in Wire Fabrics; and I do hereby declare the following to be a full, clear, and exact description of the invention, such as will enable others skilled in the art to which it app pertains to make and use the same.

My invention has for its object to provide an improved wire fabric. This fabric was especially designed for use as a wire fence, but is also capable of application to other uses.

The invention is hereinafter described, and defined in the claims.

The invention is illustrated in the accompanying drawings, wherein like notations refer to like parts throughout the several views.

In said drawings, Figure 1 is a diagram view showing the reversely - looped independent wires as they appear at the end of the first step of the process. Fig. 2 is a view showing one of the paneled sections of the fabric or the result at the end of the second step of the process. Fig. 3 is a view, partly in diagram, for illustrating the third step of the process and showing the same as completed in respect to two of the paneled sections of the fabric, but incomplete in respect to a third paneled section. Fig. 4 is a view showing the complete product or result as it appears at the end of the third step and also showing in diagram the position taken by marginal or top and bottom lock members of the marginal cables when it is desired to have the marginal wires of more than one strand, the said view showing said lock-wires in position assumed thereby before being cabled or twisted together with the marginal members of the paneled section; and Fig. 5 shows the complete fabric of the form wherein the lock-wires are included as part of the marginal or top and bottom line-wires.

Independent wires to any desired number, according to the strength desired, are first bent into similar reverse loops having right-angled legs, and these reversely - looped wires are brought into position relative to each other, as shown by the wires 1 and 2 in Fig. 1. Then one corresponding set of the loop-legs

of said wires are twisted together, thereby forming a paneled section of the fabric, (marked 3,) one of which paneled sections is illustrated detached in Fig. 2 and another as positioned near one member of another pair 55 of paneled sections previously twisted together in Fig. 3, and finally several of said paneled sections of the fabric are twisted together to complete a fabric having marginal or top and bottom strands equal in number of 60 strands to only one-half of the number of wires used for forming the similar reverse loops shown in Fig. 1. In said third step of the process the paneled sections 3 which are to be twisted together are disposed parallel 65 to each other with their hitherto - twisted legs in alinement with each other and their hitherto - untwisted legs parallel with and adjacent to each other, as shown in Fig. 3, and then the untwisted legs of the respective 70 paneled sections are twisted together to form the fabric marked 4 in Figs. 3 and 4. Then, if desired, marginal lock or reinforcing wires 5, such as shown adjacent to the fabric 4 in Fig. 4, may be added by disposing 75 said wires 5 as shown in said Fig. 4 and then twisting together the adjacent or marginal strands of the paneled sections or fabric 4 and the adjacent portions of said marginal or lock wires, thereby producing the fabric marked 80 6 and illustrated in Fig. 5. In applying the second step of the process the corresponding sets of legs of the reversely-looped wires shown in Fig. 1, which are to be twisted together, are all twisted in a common direction 85 for any given paneled section, as shown by the arrows in Figs. 1 and 2; but these twists are in reverse directions on alternate paneled sections which go into the fabric, as may be seen from an inspection of Figs. 3 and 4, 90 wherein the arrows indicate the direction of the twists. When the third step of the process is applied to cable together two such paneled sections as shown in Fig. 2, the other corresponding set of the loop-legs are all 95 twisted in a common direction. If we call the loop-legs shown as twisted together in Fig. 2 the "vertical" legs, then we may call the other legs of the loops and the paneled sections the "horizontal" legs. The horizontal 100

legs being all twisted in a common direction from central points between successive sets of the vertical legs, it follows from that fact and the reverse twists in the vertical legs that all 5 the wires of all the legs will be interlocked at the joints between the vertical and the horizontal legs and that the strands of each cable will reverse at said joints. This makes an extremely strong interlock at said joints, while 10 at the same time the said joints are sufficiently open to render the fence somewhat elastic. In fact, such an interlock will exist no difference how the paneled sections may be twisted together. Otherwise stated, the exact 15 relation of the reverse twists above noted is not essential to the interlock. It only determines the relative location of the wires which do become interlocked—to wit, as to whether one be over or under the other. Under this process 20 all the elements of the fabric are cabled together in such a strong way that the parts of the fabric cannot be pulled apart, but, on the contrary, the wires will break before they will untwist under the application of any 25 strains thereto. This has been demonstrated in practice.

It should be noted that no filling-wires are employed. The whole fabric if of the form marked 4 in Figs. 3 and 4 is made up from a 30 succession of paneled sections, such as that shown in Fig. 2, which in turn had been made from the loop-wires, such as shown in Fig. 1. The original loop-wires, therefore, when properly twisted together constitute all the longitudinal cables and all the stay-cables of the 35 fence or fabric when the fabric is in the form marked 4 in Figs. 3 and 4. The marginal or lock wires 5 may be added to afford the fabric shown in Fig. 5, having the cabled or double 40 strand marginal or top and bottom cables.

This novel fabric, whether of the form marked 4 or the form marked 6, is extremely strong, as above noted, is sufficiently elastic to readily compensate for differences of temperature, and the longitudinal members or ca- 45

bles are so interlocked with the cross members or cables that it is impossible for any slippage of one member on the other to occur. Moreover, slack can be readily adjusted as desired to adapt the fabric to any desired tension of 50 stretch. Finally, it may be added that this fabric is comparatively cheap to make.

The advantages above noted as peculiar to this novel fabric well adapt the same to the commercial demands for wire fence. 55

What I claim, and desire to secure by Letters Patent of the United States, is as follows:

1. A wire fabric composed of several paneled sections having corresponding legs thereof twisted together, and which paneled sections are formed of reversely-looped independent wires having corresponding legs thereof twisted together, substantially as described. 6c

2. A wire fabric composed of several paneled sections having corresponding legs thereof twisted together, which paneled sections are formed of reversely-looped independent wires having corresponding legs thereof twisted together, and which fabric has marginal, or top and bottom, line-cables composed of the 7c horizontal strands of the original panels and reinforcing line-wires twisted together, substantially as and for the purposes set forth.

3. A wire fabric formed of a series of line-wires reversely looped in opposite directions 75 to form vertical and horizontal strands, each composed of pairs of wires suitably twisted together substantially as described.

4. A wire fabric, composed of a series of line-wires reversely looped in opposite directions and forming vertical and horizontal strands, each consisting of a pair of wires and the wires of each strand being suitably twisted together, substantially as described. 8c

In testimony whereof I affix my signature in 85 presence of two witnesses.

THOMAS SUTHERLAND.
